UNITED STATES PATENT OFFICE.

SAMUEL M. KINTNER, OF PITTSBURG, PENNSYLVANIA, AND WILLIAM W. HANKS, OF DURHAM, NORTH CAROLINA, ASSIGNORS TO WESTINGHOUSE ELECTRIC & MANUFACTURING COMPANY, A CORPORATION OF PENNSYLVANIA.

METHOD OF SEPARATING LIQUIDS.

No. 854,295.

Specification of Letters Patent.

Patented May 21, 1907.

Application filed December 4, 1905. Serial No. 290,307.

To all whom it may concern:

Be it known that we, SAMUEL M. KINTNER and WILLIAM W. HANKS, citizens of the United States, and residents, respectively, of

5 Pittsburg, in the county of Allegheny and State of Pennsylvania, and of Durham, in the county of Durham and State of North Carolina, have invented a new and useful Improvement in Methods of Separating Liquids, of which the following is a specification.

Our invention relates to methods of separating the constituents of a mixture of liquids and it has for its object to provide a novel 15 and improved method of separating liquids having different properties.

It is a usual practice to immerse transformers and certain other electrical translating devices in oil in order that effective convection currents may be produced for cooling 20 the immersed devices. The oil also serves to improve the insulation but its dielectric strength depends largely upon its freedom from moisture.

25 The presence of moisture in oil used for cooling and insulating electrical translating devices is generally due mainly to what has been termed a breathing process that may be described as follows: When an electric device is in operation it becomes heated and warm air is driven from the receptacle containing it, while, upon discontinuing operation of the device, it cools and moisture-laden air is drawn into the receptacle where 30 the moisture condenses. Large amounts of water have in this manner been introduced into receptacles and mixed with the oil therein, the removal of which has necessitated indefinite discontinuance of operation of the 35 immersed devices.

40 Because of the difference in the specific gravity of water and that of oil, the water will settle to the bottom of the receptacle containing the mixture and we have discovered that it may then be removed by 45 means of a filter composed of plaster of paris or of some other porous substance that permits of passage of water through it but prevents the passage of oil. By a suitable arrangement of apparatus we are thus enabled 50 to remove water from oil without discontinuing the operation of the device that is immersed therein.

The single figure of the accompanying drawing is a view, partially in elevation and 55 partially in section, of means for practicing our invention.

The oil with which the receptacles for electrical translating devices are ordinarily filled may be pumped through a circulating system 60 (not shown) that comprises a settling reservoir 1, into and out of which the oil is conducted by means of inlet and outlet ports 2 and 3, respectively, the water that is mixed with the oil settling to the bottom of the reservoir. A communicating passage is provided, by means of a pipe 4, between the bottom of the reservoir and a chamber 5 in the upper part of a filtering device 6 that comprises upper and lower sections 7 and 8 having 65 a screw threaded or other connection, and a plate 9 of a suitable porous substance, such as plaster of paris, that may be formed or molded in circumferential grooves 10 in the inner surface of the lower section 8 where- 70 by it is secured in position. A valve 11 may be provided in the pipe 4 by means of which the oil may be excluded from the filter in order to facilitate cleaning and repairing there- 75 of or for other reasons, and oil and water may 80 be drained from the chamber 5 by means of an exhaust cock 12.

We have discovered that if the plate 9 is composed of plaster of paris or of some other similar porous substance, water will readily 85 pass through it but oil will not, this action being due to the fact that the liquids have different degrees of capillarity for the substance, such that water will be drawn through the plate by capillary attraction 90 while oil will not. The water may then be permitted to drop from the lower exposed surface of the plate 9 into a suitable receptacle.

We claim as our invention:

1. The method of separating liquids of different specific gravities which consist in settling the liquid of highest specific gravity and filtering it through a substance for which the liquids have different degrees of capillarity. 95
2. The method of separating liquids of different specific gravities which consists in settling the liquid of highest specific gravity and filtering it through a substance which is substantially impervious to the other liquid. 100
3. The method of separating liquids of dif- 105

ferent specific gravities which consists in settling the liquid of highest specific gravity and filtering it through plaster of paris.

4. The method of separating liquids of different specific gravities which consists in filtering the liquid of high specific gravity through a substance which is substantially impervious to the other liquid.

5. The method of separating liquids of different specific gravities which consists in filtering the liquid of high specific gravity through a substance for which the liquids have different degrees of capillarity.

6. The method of separating liquids of different specific gravities which consists in filtering the liquid of high specific gravity through plaster of paris.

7. The method of separating the constitu-

ent liquids of a mixture which consists in filtering one liquid through a substance which is substantially impervious to the other liquid.

8. The method of separating the constituent liquids of a mixture which consists in filtering one liquid through a substance for which the other has a different degree of capillarity.

In testimony whereof, we have hereunto subscribed our names this 28th day of November, 1905.

SAMUEL M. KINTNER.
WM. W. HANKS.
